SWITCH

William F. Allenby, Stratford, Conn., assignor to
 The Bryant Electric Company, Bridgeport,
 Conn., a corporation of Connecticut

Application January 28, 1950, Serial No. 141,038

9 Claims. (Cl. 200—167)

1

This invention relates to electric switches generally, and more particularly to manually operated snap switches having means for indicating their location in the dark.

Heretofore various means have been employed to illuminate switches of this type so they may be readily located in the dark. However, such prior structures have, generally speaking, required such modification or rearrangement of standard switch structures as to be relatively expensive and bulky. Accordingly, one object of this invention is to provide a simplified switch design, having novel provision for illuminating an operating handle of light transmitting material.

Another object of this invention is to provide a switch of the type described mounted in a switch casing, with a stationary light source also mounted in the casing and having novel cooperation with a switch operating handle of light transmitting material.

Still another object of this invention is to provide a novel switch casing for an illuminated switch of the type described.

These and other objects of this invention will become more apparent upon consideration of the following detailed description of a preferred embodiment thereof, when taken in connection with the attached drawing, in which:

Figure 1 is a front plan view of the switch with the cover plate broken away and the switch handle removed;

Fig. 2 is a section of the switch shown in Fig. 1, taken substantially on the line II—II of Fig. 1;

Fig. 3 is a section of the switch shown in Figs. 1 and 2, taken substantially at right angles to the section of Fig. 2, substantially on the line III—III of Fig. 2; and

Fig. 4 is a line diagram illustrating a switch embodying this invention connected in a circuit supplying an electrical load.

The particular switch 2 in which this invention is illustratively embodied, is mounted in a casing of insulating material. This casing has a bottom wall 4, side walls 6 and 8, an end wall 10 at one end of the casing, and an end-post 12 rising from bottom wall 4 at the other end of the casing, at a point intermediate side walls 6 and 8.

Terminal strips 14 and 16 are mounted on integral shoulders provided in the switch casing at each side of end-post 12, and they extend outwardly between the end-post and the respective side walls 6 and 8, to have terminal screws 17 threaded into their outer ends. Terminal screws 18 are provided in the inner ends of terminal strips 14 and 16, for a purpose to be described. Each of the terminal strips 14 and 16 have a

2

laterally and inwardly directed extension 20 which extends into proximity with bottom wall 4 of the switch casing and terminates in a laterally extending contact finger portion 22, which is spaced from the corresponding contact finger portion of the other terminal strip.

A bridging contact button 24, which is adapted to be received between contact finger portions 22 at the closed circuit position of the switch, is mounted in the lower end of a contact supporting member 26. The contact supporting member 26 is in the form of a circular segment, and should be of insulating material, preferably a material such as fiber or a molded insulating material. Contact support member 26 is supported for movement in the switch casing by a coil spring 28 which is received in an opening through an intermediate part of the contact support, and has the outer ends thereof terminating in laterally extending arms 30 having hooked ends forming pivot portions 32 adapted to be received in notches 34 provided in an abutment 36 integral with switch casing 2. Abutments 36 are provided integral with side walls 6 and 8 of the switch casing, and each abutment is provided at the top thereof with a recess 38, with notches 34 being provided in the inner wall of each recess 38.

The contact support 26 is also provided with an operating pin 40 extending therethrough and being secured at a point adjacent the apex of the contact support, with such apex part of the support being received in a slot 42 provided in the inner end of handle 41. The operating pin 40 is accommodated in grooves 44 also located in the inner end of handle 41 substantially centrally thereof. Handle 41 is of a transparent light-conducting insulating material, preferably a synthetic resin, such as a methylmethacrylate resin, all for a purpose to be described. Handle 41 is illustrated as having integral pivot lugs 46 at each side thereof to be received in semi-circular depressions 48 formed in the top of abutments 36, with the pivot lugs being held in place by a cover plate 50 for the switch casing. The cover plate may be formed of metal, and is adapted to be secured to the switch casing by screws 52, and has a central slot 56 for receiving the outer end of handle 41, with the portions of the cover plate at opposite sides of slot 56 having semi-circular formations 54 which, together with depressions 48, forms a bearing which holds handle 41 in its operative position.

The switch is shown in the drawings at its open circuit position, where bridging contact 24 is spaced away from contact finger portions 22. If

handle 41 is moved to the right from the position shown in Fig. 2, it will be observed that the contact support 26 will be moved downwardly by operating pin 40 with the latter being moved counterclockwise. This initial movement of handle 41, therefore, stresses coil spring 28, and this action continues until operating pin 40 passes to the other side of a line connecting the pivot parts 32 of coil spring 28, and the aperture through which spring 28 passes through contact support 26. At this time, the force stored in spring 22 will be operative to quickly move contact support 26 in a counterclockwise direction to forcibly move bridging contact 24 to a position between contact finger parts 22 and in engagement therewith, to thereby close the circuit between terminal strips 14 and 16. When it is desired to open the switch, handle 41 is simply moved in the opposite direction, thereby returning it to the position shown on the drawing, and the action of the parts in operating bridging contact 24 is similar to the closing operation in that energy is first stored in spring 28, and then released to move the parts to the position shown on the drawing. It will thus be apparent that the switch herein specifically illustrated is of the snap acting type, where the contacts move into and out of engagement with a rapid snap action.

In accordance with this invention, the switch casing has an integral partition 58 joining end wall 10 with the abutment 36 on side wall 8 to form a socket 60 for receiving a small lamp 62, such, for example, as a lamp of the gaseous discharge type, preferably such as a lamp filled with neon gas. Lamp 62 may illustratively have an upper portion of its envelope pinched, as at 63, where the leads to the lamp are sealed in. In the opposite corner of the switch casing there is provided a partition 64 which is integral with end wall 10 and with the abutment 36 provided on side wall 6, so as to form a socket 65 for receiving a resistor 66. The resistor may be of any well-known type having, for example, preferably a carbon resistor. The lamp and resistor are connected in series circuit relation with terminal strips 14 and 16, by one conductor 68 extending from one end of the resistor through the channel formed between side wall 6 and the upper end of its abutment 36, with the wire being held in this channel by a strip 70 of insulating material, such as fiber, which snugly fits within the channel to thus completely insulate conductor 68 from the casing cover. A second conductor 72 is connected with the other terminal of resistor 66 and one terminal of lamp 62, and extends through a notch in the outer end of partition 64. The circuit is completed by a third conductor 14 connected between the other terminal of lamp 62 and terminal strip 16, with this conductor lying in the channel formed between the upper end of the abutment 36 and the side wall 8 with which the abutment is integral. This channel is also closed by a filler strip 76 of an insulating material similar to the strip 70.

Referring now to Fig. 4, it will be apparent that lamp 62 and resistor 66 are connected in parallel with the contacts of switch 2, so that when the switch is connected in a circuit supplying a load L and the switch is closed, resistor 66 will prevent the passage of any substantial current through the lamp, and, therefore, the lamp will not be energized sufficiently to give out light. However, when switch 2 is open, the lamp 62 and resistor 66 are then in series with load L, and will be subject to sufficient voltage to light up the lamp.

It will be observed that in the open circuit position of the switch one end of the enlarged head 78 provided at the inner end of switch handle 41 will lie in proximity to the upper end of lamp 62. Moreover, the adjacent surface of handlehead 78 is an inclined surface 80 which is positioned so as to receive a substantial portion of the light rays emanating from the lamp in its socket 60 at an angle of substantially 90° with respect to surface 80, so that a substantial portion of these light rays will pass into head 78 of the handle, and due to the high index of refraction of the material employed for handle 41, the light rays will be transmitted to the handle stem. For the purpose of facilitating transmission of light rays in head portion 78 of the handle 41, all surfaces of the head portion are preferably made to be plane surfaces so that light rays striking these surfaces will be reflected at the same angle as the angle of incidence, and moreover, the outwardly projecting portion of handle 41 is also made up of a number of plane surfaces to assist in reflecting light rays to the outer tip of the handle, and, of course, to render these rays more clearly visible throughout the length of the projecting part of the handle.

From the foregoing it will be apparent that this invention comprehends the provision of a light source for illuminating a switch handle, with the light source being stationarily mounted in the switch casing and the handle having a portion cooperating therewith for transmitting light from the source to the part of the handle projecting outside of the casing. Moreover, the switch casing itself is formed in a novel manner to accommodate the light source and its series resistor, as well as the conductors connecting them across the switch terminals.

Having disclosed a preferred embodiment of the invention in accordance with the patent statutes, it should be understood that the invention is not limited to the particular structure disclosed herein, inasmuch as it will be apparent that it may be used with other types of switches, or even other types of circuit opening and closing devices. Accordingly, it is desired that the invention be not limited to the particular construction disclosed herein.

I claim as my invention:

1. A switch comprising, a switch casing, separable contacts in said casing, an operating handle of a light transmitting material movably mounted in said casing and extending through an opening in the casing so as to be operable from the exterior for actuating said contacts, a light source in said casing, said handle having an integral inner portion which is movable to and away from a position where it is in proximity to said light source to thus transmit light to the exterior of the casing at the aforesaid handle position, and said handle having a substantially plane surface in proximity to said light when the handle is at its aforesaid position, which surface is positioned substantially perpendicular to a substantial part of the light rays emanating from said source, said inner portion of said handle being in closest proximity to said light source when the light source is energized and said contacts are separated.

2. A switch comprising, a switch casing of insulating material having an open side and an opaque cover removably secured over said open side, separable contacts in said casing, actuating mechanism in said casing for actuating one of said contacts into and out of engagement with

the other, an operating handle movably mounted on said open side of the casing for operating said mechanism and having a part projecting through an opening in said cover for operation from the exterior, said casing having an integral partition 10 interiorly thereof forming a socket which extends substantially normal to said one side of the casing and is open at said one side of the casing but offset from the plane of relative movement of said contacts and handle, said socket also having a side opening facing the plane of movement of the handle, a light source mounted in said socket, and said handle having an integral inner portion which is movable to and away from a position where one side of it is opposite 15 said light source at said side opening to thus transmit light to the exterior of the casing at the aforesaid handle position, said inner portion of said handle being in closest proximity to said light source when the light source is energized and said contacts are separated.

3. A switch comprising, a switch casing of insulating material having an open side and an opaque cover removably secured over said open side, spaced fixed contacts in said casing electrically connected to terminals at the exterior of said casing, a bridging contact mounted for movement in the casing into and out of bridging relation with said fixed contacts, operating mechanism in the casing for actuating said bridging contact, an operating handle pivotally mounted on said open side of the casing for operating said mechanism and having one part projecting through an opening in said cover for operation from the exterior and another part extending into the casing to engage said mechanism, said casing having spaced interiorly located integral sockets opening only toward said one side of the casing but offset from the plane of movement of said bridging contact and handle, a light source mounted in one socket, a resistor mounted in the other socket, means electrically connecting said light source and resistor in series circuit with said fixed contacts, and said handle having an integral inner portion which is movable to and away from a position where it is in proximity to said light source to thus transmit light to the exterior of the casing at the aforesaid handle position.

4. A switch comprising, a switch casing of insulating material having an open side and an opaque cover removably secured over said open side, spaced fixed contacts in said casing electrically connected to terminals at the exterior of said casing, a bridging contact mounted for movement in the casing into and out of bridging relation with said fixed contacts, operating mechanism in the casing for actuating said bridging contact, an operating handle pivotally mounted on said open side of the casing for operating said mechanism and having one part projecting through an opening in said cover for operation from the exterior, and another part extending into the casing to engage said mechanism, said casing having spaced interiorly located integral sockets opening only toward said one side of the casing but offset from the plane of movement of said bridging contact and handle, a light source mounted in one socket, a resistor mounted in the other socket, said casing having integral interiorly located conductor receiving channels between said sockets and fixed contacts, means including conductors in said channels for connecting said light source and resistor in series circuit relation with said fixed contacts, and said handle having an integral

inner portion which is movable to and away from a position where it is in proximity to said light source to thus transmit light to the exterior of the casing at the aforesaid handle position.

5. A switch comprising, a switch casing of insulating material having an open side and an opaque cover removably secured over said open side, spaced fixed contacts in said casing electrically connected to terminals at the exterior of said casing, a bridging contact mounted for movement in the casing into and out of bridging relation with said fixed contacts, operating mechanism in the casing for actuating said bridging contact, an operating handle pivotally mounted on said open side of the casing for operating said mechanism and having one part projecting through an opening in said cover for operation from the exterior and another part extending into the casing to engage said mechanism, said casing having spaced interiorly located integral sockets opening only toward said one side of the casing but offset from the plane of movement of said bridging contact and handle, a light source mounted in one socket, a resistor mounted in the other socket, said casing having integral interiorly located conductor receiving channels which also open only toward said one side of the casing and are located between said sockets and fixed contacts, means including conductors in said channels for connecting said light source and resistor in series circuit relation with said fixed contacts, and said handle having an integral inner portion which is movable to and away from a position where it is in proximity to said light source to thus transmit light to the exterior of the casing at the aforesaid handle position.

6. A switch comprising, a switch casing of insulating material which is generally rectangular in form and open at the front side, a pair of fixed contacts in said casing at one end thereof, a bridging contact mounted in said casing for movement longitudinally of the casing into and out of bridging relation with said fixed contacts, mechanism in said casing for actuating said bridging contact, an operating handle for said mechanism mounted for pivotal movement on an axis transverse of said casing adjacent the front of the casing, a cover for the casing having an aperture for receiving a projecting part of said handle, means in one corner of said casing at the other end thereof for supporting a light source in said one corner, and said handle having an integral inner portion which is movable about the pivotal axis of the handle to and away from a position where it is opposite to the inner side of said light source to thus transmit light to the exterior of the casing at the aforesaid handle position, said inner portion of said handle being in closest proximity to said light source when the light source is energized and said contacts are separated.

7. A switch comprising, a switch casing of insulating material which is open at the front side, a pair of fixed contacts in said casing at one end thereof, a bridging contact mounted in said casing for movement longitudinally of the casing into and out of bridging relation with said fixed contacts, mechanism in said casing for actuating said bridging contact, an operating handle for said mechanism mounted for pivotal movement on an axis transverse of said casing adjacent the front of the casing, a cover for the casing having an aperture for receiving a projecting part of said handle, a socket open at the front in each of

the corners of said casing at the other end thereof, a light source in one socket, a resistor in the other socket, means electrically connecting said light source and resistor in series circuit relation with said fixed contacts, and said handle having an integral inner portion which is movable about the pivotal axis of the handle to and away from a position where it is opposite to the inner side of said light source to thus transmit light to the exterior of the casing at the aforesaid handle position, said inner portion of said handle being in closest proximity to said light source when the light source is energized and said contacts are separated.

8. A switch comprising, a switch casing of insulating material which is open at the front side, a pair of fixed contacts in said casing at one end thereof, a bridging contact mounted in said casing for movement longitudinally of the casing into and out of bridging relation with said fixed contacts, mechanism in said casing for actuating said bridging contact, an operating handle for said mechanism mounted for pivotal movement on an axis transverse of said casing adjacent the front of the casing, a cover for the casing having an aperture for receiving a projecting part of said handle, a socket open at the front in each of the corners of said casing at the other end thereof, a light source in one socket, a resistor in the other socket, means electrically connecting said light source and resistor in series circuit relation with said fixed contacts, including conductors extending along the sides of said casing between each socket and the adjacent fixed contact with said conductors located in channels formed integral with said casing and open at the front, and said handle having an integral inner portion which is movable about the pivotal axis of the handle to and away from a position where it is opposite to the inner side of said light source to thus transmit light to the exterior of the casing at the aforesaid handle position, said inner portion of said handle being in closest proximity to said light source when the light source is energized and said contacts are separated.

9. A switch comprising, a switching casing of insulating material which is open at the front side, a pair of fixed contacts in said casing at one end thereof, a bridging contact mounted in said casing for movement longitudinally of the casing into and out of bridging relation with said fixed contacts, mechanism in said casing for actuating said bridging contact, an operating handle for said mechanism mounted for pivotal movement on an axis transverse of said casing adjacent the front of the casing, a cover for the casing having an aperture for receiving a projecting part of said handle, a socket open at the front in each of the corners of said casing at the other end thereof, a light source in one socket, a resistor in the other socket, means electrically connecting said light source and resistor in series circuit relation with said fixed contacts, including conductors extending along the sides of said casing between each socket and the adjacent fixed contact with said conductors located in channels formed integral with said casing and open at the front, removable means of insulating material in each channel for retaining the respective conductors therein, and said handle having an integral inner portion which is movable about the pivotal axis of the handle to and away from a position where it is opposite to the inner side of said light source to thus transmit light to the exterior of the casing at the aforesaid handle position, said inner portion of said handle being in closest proximity to said light source when the light source is energized and said contacts are separated.
